UNITED STATES PATENT OFFICE.

JOHN T. FAGAN, OF CLEVELAND, OHIO, ASSIGNOR TO GENERAL ELECTRIC COMPANY,
A CORPORATION OF NEW YORK.

METHOD OF UNITING WIRES OF DIFFERENT SIZES.

1,206,686.

Specification of Letters Patent. Patented Nov. 28, 1916.

Application filed July 12, 1912. Serial No. 709,054.

To all whom it may concern:

Be it known that I, JOHN T. FAGAN, a citizen of the United States, residing at Cleveland, county of Cuyahoga, State of Ohio, have invented certain new and useful Improvements in Methods of Uniting Wires of Different Sizes, of which the following is a specification.

The object of the present invention is to provide an improved form of sectional leading-in conductor for incandescent lamps, in which the sections shall have their joints, or what are commonly called knots, of such diameter as to not endanger the effectiveness of the seal.

The invention comprises both such a novel form of leading-in conductor or leading-in wire and a novel method for forming the joints of sectional leading-in conductors.

20 The present application is a continuation in part of my application Serial No. 396,889 filed October 11, 1907, patented July 16, 1912 as Number 1,032,476 entitled, "Seals for sectional leading-in wires."

25 The idea of making the leading-in wires in sections arose from the necessity of having the wire, at some point in the seal, of a material which would have substantially the same co-efficient of expansion as glass. A 30 cheap conductor, such as copper, was not available for this purpose in practice. Platinum was known to have substantially the co-efficient of expansion required, but owing to its cost, it was advisable to use as little 35 as possible. In the earlier forms of lamps short lengths of platinum were led entirely through the glass seal, in which they were embedded and were secured at their ends to the conductors and to the filament. As platinum

40 became more and more expensive, certain experimenters conceived the idea of shortening the length of the platinum portion of the leading-in wire, so that it would be confined entirely within the glass seal, or, 45 at any rate, so that it would not extend clear through the same to project on both sides thereof. In endeavoring to carry out this latter idea, the platinum section of the leading-in wire was shortened so that the outer 50 end was embedded in the stem where end of the copper conductor was joined thereto, the knot or joint being thus embedded in the stem. In a few instances, the platinum section was made so short as to be entirely embedded within the glass seal, and there were

secured at the inner ends short sections of copper wire, which were extended into the lamp bulb to serve as supports for the filament.

5 The joints or knots by which the several sections were united were made before the wires were secured in the seal. These knots or joints were made by fusing the end of the copper conductor until it was sufficiently soft to permit one end of the platinum wire to 60 be inserted therein, and, by consequence of this procedure, became, as well known to every one skilled in the art, quite appreciably larger than the copper wire itself, and were objectionably large in view of the fact that 65 they were embedded in the glass seal. This arose from the fact that, upon the fusion of the end of the copper wire and the pressing of the small platinum wire into the softened mass, the fused copper, being displaced by 70 the platinum, expanded or spread laterally and gathered about the platinum in the form of an enlarged bead, which, while making an effective electrical joint, nevertheless was 75 of very markedly greater diameter than the 80 copper wire itself. Further, the form of these joints, when completed, has been almost always irregular owing to the fact that the platinum in practically every instance does not exactly strike the center of the 85 fused mass when being inserted thereinto, and also owing to other causes which will be pointed out.

When the end of the platinum wire in approaching the fused copper bead strikes 90 the bead in any way tangentially, the end of the platinum will curl to one side and project to that side when the joint is completed, resulting in a sharp lateral prong which is, when the wires are mounted in the stem, insufficiently covered by the glass. In fact, the glass sometimes is so thin over the projecting point that this seal is ineffective as a vacuum seal, even when first formed. Even should the platinum wire strike the fused copper 95 bead, approximately centrally, it happens that the copper flows or spurts unevenly to one side, resulting in a projecting spur which makes the seal defective by reason of the glass coat thereover, as in the case wherein 100 the platinum wire, itself, curls to the side. Since the thickness of the glass seal is determined in advance by the fixed distance to which the squeezing jaws can approach, it 105 cannot be changed to allow for these uneven 110

and enlarged beads, or projections or spurs, caused by the defective platinum ends and the uneven flow of fused copper. Therefore, the resulting product, when leading-in wires 5 with such joints are used, is a seal wherein the glass coating or covering is substantially thinner over the joints than over the copper section itself. This is improper and defective construction, and is the source of great 10 loss, and constitutes the reason for the art not having derived that benefit from the original idea of sectional leading-in wires which could have been derived therefrom. These unduly enlarged joints and projections 15 being coated or covered at points with a thin skin of glass, quite materially thinner than the covering of the body of the copper wire behind the joints, which latter covering is predetermined by the fixed distance between 20 the squeezing jaws of the machine employed for forming the seal, thus come so close to the surface of the glass as to endanger the seal.

It is the purpose of my invention to provide 25 electric lamps and other articles, in which sectional leading-in wires may be advantageously employed, with a seal in which the glass covering over the joints is of substantially the same thickness as the 30 covering over the larger conducting wires, for which latter covering the jaws of the machine are gaged.

Referring to the accompanying drawings 35 as illustrating certain embodiments of my invention, Figure 1 is an elevation showing an end of the copper conductor with the end of a platinum section placed in position relatively thereto to form the knot. Fig. 2 is a cross section taken on the line 2—2 of 40 Fig. 1. Fig. 3 is a plan view taken as looking down on Fig. 1. Fig. 4 is a side elevation showing the joint between the copper and the platinum sections after the fusion has taken place. Fig. 5 is a cross section 45 taken on the line 5—5 of Fig. 4. Fig. 6 is a plan view looking down on Fig. 4. Fig. 7 is a cross section showing the particular form of copper wire illustrated in Figs. 1, 3, 4, and 6, the line of section being indicated by the lines 7—7 of these figures. Fig. 8 is a cross section of a modified form 50 of copper wire, which may be used in forming the seal according to my present invention. Fig. 9 is a detail cross section showing 55 the joint embedded in the glass seal.

In the various forms shown I have provided a conducting wire A of copper, or equivalent material, which is provided with a lateral groove, channel, recess or cavity, such as B or B', into which may be placed 60 the end of a platinum section C. In forming the joint, the groove, channel, recess or cavity which I provide in the conducting wire may extend the full length of the wire, or be merely local, as the economy of manu-

facture may dictate,—it being essential that this groove, channel, recess or cavity be located at the point of formation of the knot or joint. It is essential in order to obtain the best results that the side walls of the 70 groove be smaller in section than the bottom wall thereof.

In forming the joint, the end of the platinum section C is placed within the recess provided in the conducting wire, a sufficient 75 length, and only a sufficient length, of the platinum being placed therein to form the joint successfully, and a fusing flame or arc is then directed onto the copper wire at the zone of the joint. Now, it is well known to 80 those skilled in such matter, that if the platinum wire were merely resting against a flat or convex surface of the copper wire, while the latter was being fused, the surface tension and tenacity of the skin of the copper 85 bead would be sufficient to support the platinum which would, as the bead expanded, merely rest on the surface thereof without being enveloped by the fused copper. Further, inasmuch as there is no 90 capillary attraction between metal platinum and fused copper, the contact surface between the platinum section and the copper bead would be exceedingly small, and a joint cannot be made in this manner. By 95 the method which I have devised, however, of providing the conducting wire with a previously prepared groove, channel, recess or cavity of such contour and proportion that the copper mass will partially envelop 100 the platinum section, when placed therein, the enveloping being of such extent that the fusing and spreading copper at the edges of the groove, channel, recess or cavity will surround and inclose the platinum section 105 with sufficient certainty and quickness to overcome the resistance of the surface tension of the fused conducting wire, which tends to hold the platinum section away 110 from the center of the conductor wire. The effectiveness of this formation is due to the fact that the platinum wire is partially enveloped by the copper so that the expanded fused copper presses upon the sides of the platinum in such direction as to cause the 115 flowing copper to swell thereover and embed the platinum in its mass; and also to the fact that the mass of copper at the edges of the groove, channel, recess or cavity is ordinarily of reduced thickness of mass, and presents a greater surface to the heat so that it fuses more readily than the copper in the center of the wire, and therefore has opportunity to envelop the platinum sufficiently 120 to hold it, before the copper immediately beneath the platinum becomes fused and expanded sufficiently to lift the latter away from the center of the mass.

Obviously, by this method I am enabled 125 to produce a joint in which there is no for-

mation of an enlarged copper bead and no displacement of the fused copper by the thrusting in of the platinum, and, consequently, no projecting enlargements or 5 prongs which would endanger the effectiveness of the seal. The joint formed remains of substantially the same diameter as that of the body of the conducting wire, the cavity or groove being merely filled in. No 10 expansion of moment, accidental or otherwise, exists, and the fused glass of the seal may be pressed to the predetermined thinness by the jaws of the seal-forming machine without fear of the glass covering 15 at the seal being thinner over the joint than over the body of the conducting wire. The thickness of the cover over the body of the conducting wire is, of course, quite sufficient for the purpose of forming an efficient seal, 20 and there will be no danger of the glass cover, when of this thickness, being cracked by reason of undue expansion, in any direction, of the joint.

I claim as new, and desire to secure by 25 Letters Patent of the United States:—

1. The method of uniting the ends of wires of different sizes to form a leading-in

wire for an electric incandescent lamp, the larger of said wires being of more fusible material than the smaller, which consists in 30 forming a lateral groove at the end of the larger wire, placing the end of the smaller wire therein, and fusing the metal of the portion of the larger wire in which the smaller wire lies to cause it to surround and 35 embed the smaller wire.

2. The method of uniting small wires of different sizes to form a leading-in wire for an electric incandescent lamp, the larger of said wires being of more fusible material 40 than the smaller, which consists in forming a groove at the end of the larger wire having its side walls of smaller cross-section than its bottom wall, placing the end of the smaller wire in the said groove and fusing the said side walls to embed said smaller wire. 45

In witness whereof I have hereunto set my hand this eleventh day of July, 1912.
